UNITED STATES PATENT OFFICE.

SAUL KATZ, OF NEW YORK, N. Y.

CALL-BELL.

No. 908,092.

Specification of Letters Patent.

Patented Jan. 5, 1909.

Application filed December 19, 1907. Serial No. 407,116.

To all whom it may concern:

Be it known that I, SAUL KATZ, a citizen of the United States of America, residing in the borough of Manhattan, in the city, county, and State of New York, have invented a certain new and useful Improved Call-Bell, of which the following is a specification.

The main object of my invention is to construct a simple, inexpensive and efficient 10 electrically operated call bell, which may be connected up to three different circuits, with a single battery, to give three different signals, dependent upon which of the three circuits be closed by their respective push but- 15 tons.

The view in the accompanying drawing shows a face view of the call bell, with the circuits indicated diagrammatically.

F is any usual form of metallic frame or 20 base plate supporting four binding posts 1, 2, 3 and 4, all but number 3 being electrically insulated from the frame F. This frame also supports a gong G in suitable position to be struck by the hammer H which is carried by 25 the armature D. This armature is carried by an elastic strip d secured to a projection f on the frame and it also has a spring contact d¹ normally bearing against the insulated post D¹.

To the same projection f is secured an elastic strip e carrying the "buzzer" armature E, 30 with its spring contact e¹ normally bearing against the insulated post E¹. Between the two armatures are the electro-magnets with 35 two sets of coils M, M¹, with common cores m, m. In the case illustrated, these cores extend out beyond the ends of the coils to afford a convenient means for mounting the 40 electromagnets upon supporting posts on the frame F.

The circuits are as follows: The insulating binding post 1 is connected by wire 5 to the post D¹ and thence by wire 6 to the coils M¹, and thence by wire 7 to the insulated post 2. 45 To this post 2 is connected the wire 8 with battery b, serving for all the circuits. The post 1 is connected to the battery wire 8 by wire 9 containing push button or other circuit closer S. The frame F is connected to 50 battery wire 8, through post 3 and wire 10 having push button R. The insulated post 4 is on the one side connected to the battery wire 8 through wire 11 containing push button B, and is on the other side connected 55 through wire 12 to the pair of coils M and wire 13 to the insulated post E¹.

When the push button S is pressed the circuit is closed from battery b through post 2, wire 7, coils M¹ and wires 6, 5 and 9, thus causing an attraction of the armature and a 60 single bell stroke.

When the push button R is pressed, the circuit is closed from battery b through post 2, wire 7, coils M¹, wire 6, post D¹, contact d¹, frame F, post 3 and wire 10, giving a con- 65 tinuous ring because of the making and breaking of the circuit at D¹, d¹. The buzzer E operates at the same time, but its noise is drowned by that of the gong G.

When the push button B is pressed, the 70 circuit is from battery b through post 2, wire 7, coils M¹, wire 6, post D¹, contact d¹, frame F, contact e¹, post E¹, wire 13, coils M, wire 12, post 4 and wire 11. This operates the 75 "buzzer" armature E. The windings and armatures are so adjusted that when both sets of coils M, M¹, are thus in circuit, offering increased resistance to the battery current, the electromagnets will not be sufficiently excited to actuate the gong armature D, but 80 will operate the lighter buzzer armature E.

It will be understood that the three push buttons or other circuit closers S, R and B may be located at widely different points in a building, as for example, in an apartment 85 house, to thus control with different signals, a single call bell in an apartment or room. Again the call bell is convenient for use in an office, as where a manager has to call different employees.

90

The device is simple and inexpensive to manufacture and requires but a single battery in use.

I claim as my invention:

The combination in an electromagnetic 95 call bell, comprising a metallic base, a gong, a buzzer, a hammer for the gong, and two sets of magnetic coils, three circuits, a circuit closer in each, one circuit passing through one set of the magnetic coils for a single 100 stroke, another circuit passing through the same set of magnetic coils and a circuit breaker for a continuous stroke, and, the third circuit passing through the other set of magnetic coils for operating the buzzer. 105

In testimony whereof I have signed my name to this specification, in the presence of two subscribing witnesses.

SAUL KATZ
